(57) **CLAIM**

The ornamental design for a high speed monster truck car, as shown and described.

DESCRIPTION

FIG. 1 is a front elevational view of a high speed monster truck car showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, front and left side perspective view thereof;

FIG. 9 is a top, rear and right side perspective view thereof;

FIG. 10 is a top, rear and left side perspective view thereof;

FIG. 11 is a bottom, front and left side perspective view thereof;

FIG. 12 is a bottom, front and right side perspective view thereof;

FIG. 13 is a bottom, rear and left side perspective view thereof; and,

FIG. 14 is a bottom, rear and right side perspective view thereof.
